LUBRICATING MEANS FOR SEWING
MACHINE LOOP TAKERSSydney Zonis, Stratford, Conn., assignor to The
Singer Manufacturing Company, Elizabeth,
N. J., a corporation of New Jersey

Application November 5, 1940, Serial No. 364,394

4 Claims. (Cl. 112—256)

This invention relates to rotary loop-takers for sewing machines of the type in which a thread-carrier is journaled in a raceway formed in the body of the loop-taker, the invention having for its object to provide simple but effective means for supplying lubricant to the loop-taker raceway.

With these and other objects in view, as will hereinafter appear, the invention comprises the devices, combinations and arrangements of parts hereinafter described in connection with the accompanying drawing, which illustrates a preferred embodiment of the invention and in which:

Fig. 1 is a view in front elevation and partly in vertical section, of a portion of a sewing machine containing the present improvement. Fig. 2 is a front end elevation of the loop-taker, with the thread-carrier removed therefrom.

The sewing machine shown in the drawing is, in general, substantially the same as the machine more fully disclosed in my prior patent application Serial No. 312,247, filed Jan. 3, 1940.

The sewing machine has the usual frame including a work-supporting bed-plate 1 provided with a throat-plate 2 having an aperture 3 for a vertically reciprocatory needle 4 carried by a needle-bar 5. The work is advanced by a feed-dog 6, operating through slots in the throat-plate 2 and actuated in any usual or suitable manner.

Depending from the bed-plate 1 is a bearing-lug 7 comprising one end wall of a lubricant-reservoir 8. The bearing-lug 7 has a horizontally extending aperture 9 in which a bearing-bushing 10 is secured by a screw 11 for endwise adjustment. The horizontally extending aperture 12 of the bushing 10 is provided with spaced needle-bearings 13 and 14. Journaled in the needle-bearings 13, 14 is a horizontally disposed and rotary loop-taker shaft 15 provided with a longitudinal bore 16 extending, in the present instance, throughout the length of the shaft. One end of the loop-taker shaft 15 extends into the lubricant-reservoir 8 and may be connected in any usual or suitable manner to actuating mechanism (not shown) adapted to rotate said shaft. Preferably, the loop-taker shaft 15 is driven by actuating mechanism such as fully illustrated and described in my prior patent application Serial No. 312,247, whereby the shaft 15 is rotated twice for each complete needle-reciprocation.

The opposite end of the loop-taker shaft 15 extends beyond the bushing 10, and secured upon that end of the shaft 15, by a screw 17, is the

hollow hub 18 of a loop-taker 19 of the rotary hook type and complementary to the needle 4 in the formation of lock-stitches. The loop-taker 19 has a cup-shaped body provided, in the inner face of the generally cylindrical side wall thereof, with an annular thread-carrier raceway 20.

Journaled in the loop-taker raceway 20 is the peripheral bearing-rib 21 of a thread-carrier 22 restrained against rotation with the loop-taker 19 by any usual or suitable means. The thread-carrier bearing-rib 21 is confined in the raceway 20 by the usual gib 23, and the side wall of the loop-taker is partly cut away to provide a needle-thread loop seizing beak 24.

The loop-taker 19 is preferably constructed so that the shaft aperture 25 of the hollow hub 18 extends through the bottom wall 26 of the loop-taker. The bottom wall 26 of the loop-taker is recessed in the hub-aperture thereof to receive fixedly a disk 27 disposed axially of the loop-taker and substantially flush with the inner face of the bottom wall thereof. The disk 27 forms a closure for one end of the shaft-aperture 25 of the hub and constitutes, in effect, a portion of the bottom wall of the loop-taker body. The loop-taker is preferably secured upon its shaft 15 so that the bottom-wall disk 27 of the loop-taker is spaced from the end of the shaft 15, thereby providing a hub-cavity between the shaft and disk. The disk 27 is provided with apertures 28 connecting the hub-aperture 25 of the loop-taker with the inner face of the loop-taker body, whereby lubricant supplied to said aperture 25 passes through the disk-apertures 28 in directions parallel to the axis of rotation of the loop-taker and is thereby delivered directly to the inner face of the loop-taker. The disk-apertures 28, preferably two in number, are constricted with respect to the bore 16 of the loop-taker shaft and are radially offset from the axis of rotation of the loop-taker, as well as from the bore 16 of the loop-taker shaft; said apertures 28 being preferably spaced from each other diametrically of the disk 27. While it is preferred to employ the apertured disk 27, set into the body of the loop-taker, it is to be understood that the disk portion of the loop-taker may be formed integral with the loop-taker body.

Extending through the longitudinal bore 16 of the loop-taker shaft 15 is a lubricant-conducting wick 29, of which one end extends beyond the end of the shaft 15 into the loop-taker hub-cavity and preferably into contact with the disk 27 between the apertures 28 thereof. Lubricant is supplied to the other end of the wick 29 from the

reservoir 8 in the manner fully described in my prior patent application Serial No. 312,247. The wick 29 conducts the lubricant lengthwise of the shaft 15 and thereby delivers lubricant to the hub-cavity 25 and to the apertures 28 of the disk 27. The wick 29 serves to control the quantity of lubricant supplied to the disk-apertures 28, and the offset constricted apertures 28 further control the delivery of the lubricant to the inner face of the bottom wall 26 of the loop-taker, along which face the lubricant is impelled by centrifugal force and thence passes along the side wall of the loop-taker to the thread-carrier raceway.

The improvement described therefore provides controlled means for delivering lubricant directly from the bore and substantially axially of the loop-taker shaft to the inner face of the loop-taker body, thereby obviating the necessity of providing radial and other special lubricant-guiding ducts heretofore employed in devices of this general character.

Having thus set forth the nature of the invention what I claim herein is:

1. In a sewing machine having stitch-forming mechanism including a rotary loop-taker shaft provided with a longitudinal bore open at one end of said shaft, a loop-taker having an axially apertured hub and a cup-shaped body comprising a generally cylindrical side wall and a bottom wall, means for securing said loop-taker upon said open end of the loop-taker shaft with the bottom wall of the loop-taker disposed in spaced relation to said end of the shaft, thereby to provide in the hub of the loop-taker a lubricant-cavity closed at one end by a portion of said bottom wall of the loop-taker, said side wall of the loop-taker body being internally provided with a thread-carrier raceway, and a thread-carrier journaled in said raceway and restrained against rotation with said loop-taker, the improvement which consists in the provision in the hub-cavity end closure portion of the bottom wall of said loop-taker of a lubricant-conducting aperture connecting said lubricant-cavity with the inner face of said loop-taker in a direction substantially parallel to the axis of rotation of the loop-taker, said lubricant-conducting aperture being constricted relatively to the bore and offset from the axis of rotation of said shaft, and a lubricant-conducting wick disposed in the bore of said shaft and having one end thereof disposed in contact with the outer face of the bottom wall of the loop-taker adjacent the aperture in said bottom wall.

2. In a sewing machine having a rotary loop-taker shaft lengthwise provided with a lubricant-

conducting bore open at one end of said shaft, a rotary loop-taker having a cup-shaped body including a bottom wall provided with a hollow hub carried by the open-bore end portion of said shaft, said bottom wall of the loop-taker body having a portion thereof forming a closure for one end of said hollow hub, and a thread-carrier journaled in said loop-taker body and restrained against rotation therewith, the improvement which consists in the provision in the hub end-closure portion of said bottom wall of a lubricant-conducting aperture connecting the hollow of said hub with the inner face of said loop-taker bottom wall, said lubricant-conducting aperture extending lengthwise of said shaft.

3. In a sewing machine having a rotary loop-taker shaft lengthwise provided with a lubricant-conducting bore open at one end of said shaft, a rotary loop-taker having a cup-shaped body including a bottom wall provided with a hollow hub carried by the open-bore end portion of said shaft, said bottom wall of the loop-taker body having a portion thereof forming a closure for one end of said hollow hub, and a thread-carrier journaled in said loop-taker body and restrained against rotation therewith, the improvement which consists in the provision in the hub end-closure portion of said bottom wall of a lubricant-conducting aperture extending lengthwise of said shaft and connecting the hollow of said hub with the inner face of said loop-taker bottom wall, said lubricant-conducting aperture being radially offset from the axis of rotation of said loop-taker and being constricted relatively to the bore of said shaft.

4. In a sewing machine having a rotary loop-taker shaft lengthwise provided with a lubricant-conducting bore open at one end of said shaft, a rotary loop-taker having a cup-shaped body including a cylindrical side wall and a bottom wall, said side wall being internally provided with a thread-carrier raceway and said bottom wall having a hollow hub carried by the open-bore end portion of said shaft, a thread-carrier journaled in said raceway and restrained against rotation with said loop-taker, and a disk carried by said bottom wall of the loop-taker and forming a closure for one end of said hollow hub, the improvement which consists in the provision in the hub end closure disk of a plurality of lubricant-conducting apertures radially offset from the axis of rotation of said loop-taker and connecting the hollow of said hub with the inner face of said loop-taker bottom wall, said lubricant-conducting apertures extending lengthwise of said shaft.

SYDNEY ZONIS.
